UNITED STATES PATENT OFFICE

166,927

MOTH REPELLENT CONTAINER
OR THE LIKE

Alvin L. Saeks, Clayton, Mo., assignor to The
Puro Co., Inc., St. Louis, Mo., a corporation of
Missouri

Application February 4, 1952, Serial No. 18,357

Term of patent 14 years

(Cl. D16--2)

To all whom it may concern:

Be it known that I, Alvin L. Saeks, a citizen of the United States, residing at Clayton, county of St. Louis, State of Missouri, have invented a new, original, and ornamental Design for a Moth Repellent Container or the like, of which the following is a specification, reference being made to the accompanying drawing forming a part thereof, in which,

Figure 1 is a front elevational view of a moth repellent container or the like embodying my new design;

Figure 2 is a side elevational view thereof;

Figure 3 is a top plan view thereof; and

Figures 4 and 5 are transverse and longitudinal sectional views, respectively, thereof taken along lines 4-4 and 5-5 of Figure 1.

I claim:

The ornamental design for a moth repellent container or the like, substantially as shown.

ALVIN L. SAEKS.
